LETTERING BRUSH

Edwin C. Wood, East Orange, N. J.

Application May 23, 1933, Serial No. 672,393

13 Claims. (Cl. 120—111)

My present invention relates to an improvement in sign writing implements and has for its particular features an improvement in lettering stylus hereinafter called a brush for use in lettering signs with drawing ink or its equivalent.

The main object is to increase the ink holding and retaining capacity of such a stylus or "brush", and further to improve the manner of filling or charging the stylus with ink to its capacity and with cleanliness and speed.

Another feature lies in the provision of contour variants in the writing surfaces of such brushes, whereby the type of letter, its thickness in its various letter proportions may be varied during the stroking of the brush to form the letter.

Other features will be apprehended as the herein description proceeds and it is obvious that modifications may be made in the structures herein disclosed without departing from the spirit hereof or the scope of the appended claims.

In the drawing,

Fig. 1 is a longitudinal section of one form of stylus, showing the details thereof;

Figs. 2—3 and 4, are sectional views taken on lines 2—2, 3—3 and 4—4 Fig. 1, looking in the direction of the arrows;

Fig. 5 is an enlarged fragmental partially sectioned view of the stylus point of Fig. 1;

Fig. 6 is a characteristic ink stroke made by the stylus point of Fig. 1;

Fig. 7 is a view in elevation, of the capillary reciprocable ink retaining core and its assembled plunger connections;

Fig. 8 is an enlarged end view of Fig. 1;

Fig. 9 is a view of an alternate form of capillary reciprocable ink retaining core for a brush type of lettering stylus;

Fig. 10 shows a modified broad or brush type of brush stylus;

Fig. 11 is a sectional view taken on the line 11—11, Fig. 10 looking in the direction of the arrows;

Fig. 12 is a fragmented side view of the brush end of the stylus shown in Fig. 10;

Fig. 13 is an enlarged fragmentary view in elevation, of the ink holding core of Fig. 10, showing the capillary ink holding channels;

Fig. 14 is a sectional view of Fig. 13 taken on line 14—14 looking in the direction of the arrows;

Fig. 15 is an end view of Fig. 13 showing the core point and the manner of channeling to provide ink retaining and flow capillaries;

Fig. 16 is a greatly enlarged, fragmented cross section taken on line 16—16, Fig. 13, looking in

the direction of the arrows, to show one form of capillary ink retaining channels;

Fig. 17 is an elevational view, fragmented, to show another core having capillary ink retaining channels for the stylus form of writing device;

Fig. 18 is an end view thereof;

Fig. 19 shows a characteristic ink stroke of the brush of Fig. 10, made with its narrow face;

Fig. 20 illustrates another characteristic ink stroke made with the flat, or broad face of the brush of Fig. 10;

Fig. 21 is a fragmented brush end of the core like that of Figs. 10 and 13 showing gaps in the body thereof, to make ink strokes like that shown in Fig. 22;

Fig. 22 shows a mark made by a pen constructed as shown in Fig. 21;

Fig. 23 is an enlarged fragmentary view of the stylus end of the device of Fig. 1, shown in section;

Fig. 24 is a side view of the plunger shown in Fig. 9;

Fig. 25 is a fragmented sectional view of a stylus end with end capillaries; and

Fig. 26 is an end view of Fig. 25 showing the capillary channels in the end face thereof.

In the present device, the structural features in the two forms shown in the drawing are substantially alike, and accordingly, like parts bear the same indices in the various views, where the structures or functions thereof are alike.

In Fig. 1 is shown one form of lettering implement, and inasmuch as its lettering point is cylindrical in contour, it is herein referred to as a stylus. It comprises an outer cylindrical casing, preferably of a phenolic condensation compound, such as Bakelite, or its equivalent, in the bore of which is mounted a manually reciprocable plunger-ink retainer assembly, shown in Fig. 7. In this latter figure, there is shown a wire rod 8 having fixed on its upper end, a plunger cap 9, its lower end having affixed thereto a capillary ink-retaining core 2. As in Fig. 1, the lower end of the casing is threadedly connected at 3, to a metallic stylus point 1, the shoulder 4 thereof engaging the lower edge of the cylinder in a friction tight fit.

Due to the reciprocal action of the assembly 2—8—9 within the bore of the casing 5, especially when the capillary core 2 is being charged, and when being unloaded of its ink charge during the lettering action, a vent 6, Fig. 1 must be provided so that the act of charging the stylus with ink and its automatic discharge from the stylus is smooth in action, and instantaneous. The vent 110

6 may be placed in the upper part of the stylus point 1. In general the vent should be above the ink line of the ink core 2 when it is in its upper operative position as in Fig. 1.

5 As in Figs. 1 and 23, the plunger rod assembly 2-8-9 is held upwardly in operative position by a coiled spring 7, which extends between and contacts with the under shoulder of head 9 and the upper shoulder at the threaded end 3 of the 10 stylus 1, as in Fig. 23, the spring 7 being threaded on the rod 8. As this constructed pressure upon 9, thrusts the capillary ink retaining core 2 downwardly and out of stylus 1, it is then dipped in a fluid writing medium such as a drawing ink, or 15 the like, and because of the construction of the core 2, later to be described, the core is immediately charged with the ink, upon which the plunger 9 is released, and the capillary core 2 is drawn back into the stylus, to its lettering position, as in Figs. 1, 5 and 23.

20 In all figures where the capillary ink holding core 2, hereinafter referred to as the core, is shown, it will be noted that it comprises a body 2, preferably of metal though other non-metallic materials may be used, of any desired cross section, that is, it may be cylindrical as in Figs. 1-4 and 25 18, or rectangular, as in Figs. 10 and 15. Further, the body 2 is provided with a plurality of fine, or extremely narrow capillary grooves G 30 therein.

35 In cylindrical pointed stylus like that of Figs. 1-4 and 18, of extremely small diameter, the core 2 will naturally be of small diameter and the capillaries G will, if of necessity be few in number and extremely small. As the stylus is increased in diameter, the core increases in diameter and naturally the number of capillaries G are increased, greatly increasing the ink storage capacity. It has been found by experiment, though 40 not necessarily being a limitation, that cores, with the larger proportion of their capillary channels G cut longitudinally thereof give a more even discharge of writing fluid in use, down to the last drop of fluid held therein, and the ink flow from 45 the stylus at the beginning of the use of a fully charged stylus, does not flood out. Thus the capillaries not only greatly increase the ink carrying capacity of the stylus or brush but fully control the ink discharge therefrom, evenly, from the 50 fully charged to the final empty condition of the core.

55 In the cylindrical type of core, as in Figs. 5 and 8, the channels G are cut longitudinally of the core 2, and as in Fig. 8, are sunk in, radially, as deep as is permissible, without cutting through or into one another. These cuts may be from 60 .01 to .02 of an inch in width depending upon the viscosity of the fluid used and of any permissible depth, depending on the dimensions of the core.

65 It has been noted, in practice, that it is not necessary to plunge the core into the writing medium its full length to charge it, if it is dipped in the writing medium only a short distance of its length it immediately fills, through capillary attraction, to the full extent of its capillary capacity.

70 In the brush type of implement, as shown in Figs. 9 to 16, and 21, there is disclosed a brush core 2 preferably made of celluloid or like material, and which is rectangular in cross-section, being narrow in one dimension and wide at its other dimension, and is thus capable of making a thin line as in Fig. 19, D when it is moved in the direction of the arrow D, Fig. 10, and is capable of making a solid broad line, as E, in Fig.

20, or any intermediate width of line between the dimensions of the two lines D and E.

80 In using both the stylus and brush types, they are held vertically to the surface being printed or written upon as at Fig. 5, where the stylus of Fig. 1 is shown with its point and core squarely set upon the writing or printing plane P, thus to create a line like that shown at F in Fig. 6, when moved in the direction of the adjacent arrow.

85 To create the necessary capillary action for holding the extra supply of ink in the brush 2 of Fig. 10, as will be noted, the core end 2, the amplified exterior surface of the core is cut into by a series of narrow, deep capillary channels, generally denoted by G, in the enlarged views 13, 90 14, 15 and 21. In the said views the both wide sides of the bore are cut into, and as indicated in the still further amplified view of Fig. 16, 95 which is a section taken on line 16-16, Fig. 13, these cuts G are staggered, so that each alternate top and bottom cut, Fig. 16, is overlapped by the alternate opposite cut, at their respective bottoms. This thus provides for deep narrow capillary ink retaining channels of considerable storage capacity, having such ideal surface tension, that considerable ink may be drawn into the channels G and held with little tendency of release therefrom except when in contact with the writing surface P, Fig. 5.

100 In order to provide a freely acting outlet for the stored ink in the body of the core 2, Figs. 10 and 12, and also to provide a narrow transverse writing point the front writing edge of the core 2, as in Figs. 12 and 14, is tapered on both faces 110 thus leaving a narrow writing face 10. This writing face 10 is traversed by a narrow capillary channel H, Figs. 14 and 15, which latter is a front view of said writing face. Further it will be noted that the top capillaries G, Fig. 14, 115 are cut so that their bottoms I are in the same plane as the bottom of writing slot H, fully shown by the indice H, and the associate dotted lines, Fig. 16.

120 Thus constructed, it will be noted that all the capillaries G and H, as to provide for full width of ink flow without gaps for any stroke of the brush 2 of Fig. 10, the writing capillary H, creating a solid line across the face of the width for the solid wide stroke and the storage capillaries 125 G due to their bottom overlap as in Fig. 16, feeding smoothly into H, and providing for a solid line the full width of the narrow stroke, as in Fig. 19.

130 The other details of the structure of the brush, Fig. 10, are as follows, the outer box like casing 5 is of rectangular cross section, and is hollow, and reciprocably mounts a rectangular plunger construction shown in Fig. 9, comprising a manually manipulable head 9, a brush end 2, having the before described capillaries G and H, with 135 the tapered narrow writing face 10. The core 2 is joined to the head 9 by two narrow connecting arms 8-8 which are spaced apart to form a spring slot 7', in which slot is mounted a spring 7, Fig. 10, the other end of the compression spring 140 7 rests against a pin 13, which is passed through and fixedly mounted in the casing 5, and rides in slot 7'. Two similar pins 12, 12 similarly mounted, act as abutment stops for the back movement of the plunger, as they contact with 145 the shoulders 14-14 of the plunger. A vent 6 is also provided for the same purpose as described for Fig. 1.

150 The plunger core center, between the capillary end and the head end 9 is thinner, between

the lines 17—18, including the ribs 8—8, than the thickness shown in Fig. 11, this being shown by the dotted lines 19, Fig. 12. This is for the purpose of preventing the ink, during use and filling from capillary creeping up, within the casing, to the head 9.

When the plunger head 9 is pressed, the plunger structure is pushed forward from its operative writing position to the ink charging position A, shown dotted, in Fig. 10. To charge the core 2 with ink it is only necessary to dip the core part way into a writing medium and it immediately picks up a charge.

In sign writing or lettering, the writing point 10 is normally extended beyond the adjacent end 15 of casing 5, as in Figs. 10 and 12, a short distance only, and it is ready for operation.

In Fig. 21 there is shown a fragment of an enlarged core G, as in Fig. 10, in which the core 20 has non-capillary slots 11—11 cut therein so as to provide for clear lines 16—16, Fig. 22, in the black line. In some forms of lettering these clear lines or stripes add attractive effects to the lettering.

25. Another form of cylindrical stylus is shown in Figs. 17 and 18, the difference being in the arrangement of the storage or feeder capillaries and the writing capillaries. In Fig. 10 the storage capillaries have their own writing outlets as well 30 as feed into the feeding outlet H, whereas in the modification shown in Figs. 17 and 18, the core 2 is cylindrical, is provided with a plurality of spaced annular storage capillaries G, and these are traversed by a plurality of vertical writing or 35 feeding capillaries J, which are radially cut into the cross sectional area, Fig. 18, and thus join all the annular storage capillaries above the writing face 10.

In Figs. 25—26, there is shown a further provision of capillary channels, these, however being provided in the end face of the stylus casing 1, as at 20'. These capillary grooves 20' are cut into the end face of the stylus casing 1, and control the precise flow of ink from the core 2, across the 45 writing face of the casing 1.

In all forms of capillary core shown in the various figures it is to be understood that the bore of the portion of the stylus or casing immediately surrounding the capillary core, or ink holding 50 portion, is somewhat larger in dimension than the core itself, and that, therefore, the inner wall surface of the stylus or casing itself also creates a surrounding capillary about the core, and also serves to hold the ink in reserve until used by lettering. In practice the core itself may be smaller in dimension than the bore of the casing to accomplish the same results. This capillary space is shown at 20, Fig. 23.

In either form, as above noted, the ink storage 60 capacity is greatly increased and adds to the perfect action of the brush.

Having thus described the invention what I claim is:

1. A lettering brush comprising an outer casing 65 having a stylus thereon, a capillary ink retaining core therein, means for manually projecting said core from the stylus and means for automatically retracting said core.

2. A lettering brush comprising an outer casing 70 having a stylus thereon, a capillary ink retaining core therein, means for manually projecting said core from the stylus, means for automatically retracting said core and a vent located adjacent to said core.

75. 3. A lettering brush, including a casing having

a stylus thereon, a fluid retaining core therein, means for manually projecting said core from the stylus to charge it with fluid, and means for retracting the core into the casing after charging, said core being provided with a plurality of capillary channels therein.

4. A lettering brush, including a casing, a capillary fluid retaining core therein, means for manually projecting said core from the casing to charge it with fluid, and means for automatically retracting the core into the casing after charging, said core being provided with a plurality of intercommunicating capillary channels therein.

5. A lettering brush, including a casing, a capillary fluid retaining core therein, said core being provided with a plurality of intercommunicating capillary channels therein, means for manually projecting said core from the casing to charge it with fluid, means for automatically retracting the core into the casing after charging, and means for stopping the core in its retracted position in lettering relation to the casing.

6. A lettering brush comprising an outer casing, a channeled, capillary ink retaining core therein, means for manually projecting said core from the casing, means for automatically retracting said core, a vent located adjacent to said core and means for positioning the end of said core in spaced lettering relation to the end of said casing.

7. A lettering brush comprising an outer casing having a stylus thereon, a channeled, capillary ink retaining core therein, a plunger for manually projecting said core from the stylus, a spring in said casing, for automatically retracting said core, a vent located adjacent to said core and stops in said casing for positioning the end of said retracted core in flush lettering relation to the end of said stylus.

8. A lettering brush, including a casing, a fluid retaining, lettering core therein, means for manually projecting said core from the casing to charge it with fluid, means for automatically retracting the core into the casing after charging, said core being provided with a plurality of capillary fluid storage channels therein, the lettering face of said core being provided with a capillary channel.

9. A lettering brush, including a casing, a fluid retaining, lettering core therein, means for manually projecting said core from the casing to charge it with fluid, means for automatically retracting the core into the casing after charging, said core being provided with a plurality of capillary fluid storage channels therein, the lettering face of said core being provided with a capillary channel, all of said fluid storage channels being in communication with the channel on said lettering face.

10. A lettering brush, including a casing, a fluid retaining lettering faced core therein, means for manually projecting said core from the casing to charge it with fluid, and means for automatically retracting the core into the casing after charging, said core being provided with a plurality of capillary ink storage channels therein, the lettering face of said core being tapered and having a lettering capillary channel therein with which said capillary ink storage channels communicate.

11. A lettering brush comprising an outer casing having a stylus thereon, a channeled, capillary ink retaining lettering core therein, means for manually projecting said core from the casing, means for automatically retracting said core,

a vent located adjacent to said core and means for positioning the lettering face of said core in lettering relation to the end of said stylus, the capillary channels extending to the lettering face of said core.

12. A lettering brush, including a casing, a capillary fluid retaining core therein, means for manually projecting said core from the casing to charge it with fluid, and means for automatically 10 retracting the core into the casing after charg-

ing, said core being provided with a plurality of capillary channels therein and being spaced from the walls of said casing.

13. A lettering brush comprising an outer casing having a stylus thereon, a reciprocatable, 80 channeled capillary ink retaining core therein, both the face of the stylus and the core forming a common writing face and plural capillary grooves in the writing face of said stylus and core.
